UNITED STATES PATENT OFFICE.

HENRY LUCAS ROBERTS, OF GRIMSBY, ONTARIO, CANADA.

REFRIGERATOR.

Application filed June 28, 1926. Serial No. 118,154.

My invention relates to improvements in refrigerators and the object is to provide a novel form of refrigerator which will be exceptionally economical and efficient in operation and in which a very dry atmosphere will be maintained.

A further object is to eliminate to a great extent the loss due to warming of the refrigerator ordinarily caused during the opening 10 and closing of the refrigerator to get at articles placed therein.

A further object is to improve the cleanliness and convenience of operation by having the ice entirely enclosed in a removable watertight container, which may be entirely removed from the refrigerator for filling and emptying, thus keeping the refrigerator clear from all dirt or foreign matter on the ice.

Other objects will appear in the course of 20 the following specification.

My invention consists in the construction and arrangement of parts, all as hereinafter more particularly described and illustrated in the accompanying drawings in which:—

25 Fig. 1 shows, in diagrammatic form, a central vertical section through a refrigerator embodying my improved construction.

Fig. 2 is a side elevation of an improved ice container used in my invention.

30 In the drawings, like characters of reference indicate corresponding parts in the two views.

In the form illustrated, my invention consists of a refrigerator, the casing 1 of which 35 is of standard insulated construction.

A horizontal partition 2 extends across the refrigerator in spaced relation from the top thereof so as to form a chamber 3 at the top of the refrigerator.

40 This partition 2 is provided with a central opening or port 4 and above this port is a baffle 5.

At the top of the chamber 3 the casing 1 is provided with an inlet port 6 and an outlet 45 port 7. Covering the port 6 is an ordinary flap valve 8 which operates as an inlet valve and covering the port 7 is a similar outlet valve 9.

The chamber 3 constitutes a compensating 50 chamber as will be later explained.

Immediately below the partition 2, the front wall of the casing 1 is provided with a circular orifice 10 to permit insertion of a watertight ice container 11.

55 This container comprises a cylindrical pail-like portion 12 and a lid 13 which has

threaded engagement in the open end of the portion 12 and forms a closure therefor.

This lid 13 is of novel construction and in the form illustrated comprises a threaded 60 cap portion 14 which has threaded engagement in the end of the portion 12.

This cap 14 has an enclosed central air chamber 15 which acts as an insulator.

Secured to the portion 14 is an outer cap 65 16, the interior of which is filled with heat insulating material 17 and between the portions 16 and 17 is a wooden disk 18.

The portion 16 is formed with an undercut shoulder 32 so that when the container is 70 inserted into position within the refrigerator the portion 16 forms a closure for the opening 10 in the casing, the shoulder 32 abutting against a rubber annulus 19.

Extending across the refrigerator are horizontal strips 20 which form supports upon which the container 11 rests.

Secured to these supports immediately below the container 11 is an absorbent strip 21 which extends outwardly through the rear 80 wall of the casing as indicated at "B".

This absorbent strip 21 constitutes a wick positioned centrally below the container and adapted to receive all drip from the exterior surface thereof.

85 This wick is not the full width of the refrigerator but is comparatively narrow so that ample space is left at each side thereof to permit free air circulation therewith as will presently be explained.

90 The lower portion of the refrigerator below the container 11 is occupied by a number of drawers 22—23—24 and 25, which drawers may be the full width of the refrigerator and extend inwardly from the front 95 thereof.

The drawers are superimposed one above the other and each drawer is of somewhat shorter length than the drawer next below so that when pushed fully in there is an uncovered space indicated at "A" at the rear end of each drawer which spaces provide an opening at the rear of each drawer for the admission of cold air thereto.

100 Between adjacent drawers are partitions 26, these partitions extending the full width of the refrigerator and to a distance into the refrigerator from the front thereof equal to that of the drawer next above.

105 These partitions form supports for the 110 drawers.

The front wall of each drawer is insulated

in the same manner as the refrigerator casing and each drawer is provided with any suitable handle 27.

5 A quantity of ice in the container 11 is indicated in the drawings by numerals 28, water formed from the melting of this ice being indicated by the numeral 29.

A handle 30 is provided on the lid 13.

10 The operation of my refrigerator is as follows:—

In filling the refrigerator with ice the ice-man withdraws the entire container 11 taking it out of the house to his wagon.

5 The cover 13 is then removed, any water in the container being emptied and the container is filled with ice after which the cover 13 is replaced.

20 He then replaces the container in the refrigerator and, when pushed fully in, the lid 13 forms a secure closure for the opening 10 in the refrigerator.

25 It is to be understood that the lid 13 forms a watertight closure for the container so that the ice and all water formed from the melting thereof remains within the container.

The air in the refrigerator is cooled and falls entering and filling the drawers through the openings "A" at the rear ends thereof.

30 As previously stated the wick 21 is comparatively narrow so that ample clearance is provided at each side thereof to permit free circulation of air therewith and therefore the wick does not prevent the circulation 35 of air from the upper part to the lower part of the refrigerator and vice versa.

40 By my construction, whereby the air does not contact directly with the ice, considerably greater economy is obtained and also a very dry atmosphere is maintained in the refrigerator.

45 Any moisture in the refrigerator which will condense on the exterior surface of the container will drip onto the absorbent strip 21, which strip will act as a wick and conduct this moisture outwardly through the casing to be evaporated from the portion "B" which projects into the outer air.

50 In this way moisture is removed from the interior of the refrigerator so as to insure a very dry atmosphere therein which of course is very desirable.

55 When any one of the drawers is drawn out, air from the compensating chamber 3 will be drawn downwardly through the opening 4 in the partition 2 to compensate from the displacement of the withdrawn drawer and air will be drawn inwardly into the chamber 3 past the valve 8 but none of this 60 warm air from the outer atmosphere will pass through the opening 4 and will thus affect no warming of the portion of the refrigerator below the partition 2.

65 Also the opening of the drawer will not permit any inrush of warm air into the re-

frigerator since the opening in the refrigerator casing is at all times completely closed by the drawer. In this connection it is to be noted that the top edges of the drawers are a snug sliding fit against the partitions 26.

Also since the drawers remain at all times horizontal, when a drawer is partially withdrawn, there will be no spilling of the cold air out of the drawer so that when it is again 75 pushed inwardly the same cold air remains in it as was there before it was opened.

When the drawer is again closed, air is driven upwardly through the opening 4 and air from the compensating chamber 3 passes 80 outwardly past the outlet valve 9.

The compensating chamber 3 has a cubic capacity not less than that of the largest drawer so that no cold air is wasted in closing the drawer nor is any warm air from the 85 outer atmosphere drawn past the opening 4 in the partition 2 during the opening of the drawer.

The baffle 5 is provided immediately above the opening 4 in the partition 2 to deflect 90 the cold air passing upwardly through the opening 4 during the closing of the drawer downwardly in the direction of the arrows "C" so that this air does not pass directly to the outlet valve 9. Also additional baffles 31 95 are placed in front of the ports 6 and 7 so that the air passing inwardly or outwardly through these ports must come from the extreme upper portion of the chamber 3.

It will thus be noted that in my refrigerator the refrigerating compartment is practically always closed even when the drawers are drawn out so that there is not free communication between the interior of the refrigerator and the outer air as is the case 105 with the ordinary refrigerator having doors and this results in a very greatly increased economy in the use of ice.

The partitions 26 are so positioned that the tops of the drawers are a very snug sliding fit thereagainst, this being necessary to maintain the economy referred to above.

110 A feature of my invention is that, by having the ice enclosed entirely in a watertight container, the refrigerator may be maintained in a much cleaner condition so that no dirt or foreign matter on the ice has to be contended with.

115 A further convenience is that the operation is much more convenient for the housewife since no provision has to be made for catching the water caused by the melting of the ice. Also there is no loss of cold air through a drain pipe as is the case with the ordinary type of refrigerator.

120 One of the most serious causes of the wasteful use of ice in the ordinary refrigerator is due to the warming of the refrigerator and the loss of cold air therefrom when the doors are opened.

This disadvantage is entirely done away with in my refrigerator since as stated above, the opening of the drawers does not permit the escape of any cold air or the inrush of any warm air.

While I have illustrated and described the use of one container 11 only, any desired number could be used in which case they might be placed horizontally side by side 10 and a wick 21 would be placed below each container.

From the foregoing it will be apparent that I have devised a novel type of refrigerator whereby the objects of my invention 15 have been attained.

Various modifications may be made in my invention without departing from the spirit thereof or the scope of the claims and therefore the exact forms shown are to be taken 20 as illustrative only and not in a limiting sense and I desire that only such limitations shall be placed thereon as are imposed by the prior art or are specifically set forth in the appended claims.

25 What I claim as my invention is:

1. In a refrigerator, an enclosed water-tight ice container, and a wick below said container extending outwardly through the refrigerator casing and positioned to receive all drip from the exterior surface of the container.

30 2. In a refrigerator, an enclosed water-tight ice container supported in the upper portion thereof, a wick below said container positioned to receive all drip from the exterior surface thereof, said wick extending outwardly through the refrigerator casing, and a plurality of drawers in the lower portion of the refrigerator.

35 3. In a refrigerator, an enclosed water-tight ice container supported in spaced relation from the top thereof, a plurality of drawers below said container, the portion of the refrigerator above said container forming an air chamber, and an inlet and an outlet valve communicating between said chamber and the outer air.

40 4. In a refrigerator, an enclosed water-tight ice container supported in spaced relation from the top thereof, a plurality of drawers below said container, the portion of the refrigerator above said container forming a chamber, the cubic capacity of which is not less than that of the largest drawer, 45 and an inlet and an outlet valve communicating between said chamber and the outer air.

50 5. In a refrigerator, an ice container in the upper portion thereof, a plurality of drawers in the lower portion of the refrigerator, said drawers superimposed one above the other, each drawer being somewhat shorter in length than the drawer next below so as to leave an uncovered space at the rear end of each drawer when the drawers are pushed 55 fully inwardly.

6. In a refrigerator, an ice container in the upper portion thereof, a plurality of drawers in the lower portion of the refrigerator, said drawers superimposed one above the other, each drawer being somewhat shorter in length 70 than the drawer next below so as to leave an uncovered space at the rear end of each drawer when the drawers are pushed fully inwardly, and a horizontal partition between each drawer and the one next above, said partition forming a closure for the top of the drawer therebelow with the exception of the aforesaid uncovered space at the rear end of the drawer.

7. In a refrigerator, an enclosed ice container supported in spaced relation from the top thereof, the portion of the refrigerator above said container forming a chamber, the casing of the refrigerator having ports therethrough at the top of said chamber, automatic inlet and outlet valves controlling the opening and closing of said ports, a plurality of drawers in the lower portion of the refrigerator below said container, said drawers superimposed one above the other, each 80 drawer being somewhat shorter in length than the drawer next below so as to leave an uncovered space at the rear end of each drawer when the drawers are pushed fully inwardly, 85 the cubic capacity of the chamber at the top of the refrigerator being not less than that of the largest drawer.

8. In a refrigerator, an enclosed ice container supported in spaced relation from the top thereof, the portion of the refrigerator above said container forming a chamber, the casing of the refrigerator having ports therethrough at the top of said chamber, automatic inlet and outlet valves controlling the opening and closing of said ports, a plurality of drawers in the lower portion of the refrigerator below said container, said drawers superimposed one above the other, each drawer being somewhat 90 shorter in length than the drawer next below than that of the largest drawer. 95 so as to leave an uncovered space at the rear end of each drawer when the drawers are pushed fully inwardly, the cubic capacity of the chamber at the top of the refrigerator being not less than that of the largest drawer, 100 and a wick below said container positioned to receive all drip from the exterior surface thereof, said wick extending outwardly through the refrigerator casing.

105 9. In a refrigerator according to claim 3, a horizontal partition above the container forming the bottom of the compartment in the upper part of the refrigerator, said partition having a port therein forming a communication between the chamber and the remainder of the refrigerator, and a baffle positioned above said port.

110 10. In a refrigerator according to claim 3, flap valves associated with the ports in the upper chamber.

- 4
11. In a refrigerator, an enclosed water-tight ice container in the form of a cylindrical vessel, a removable insulated cover for the open end thereof, the refrigerator casing having a circular orifice adapted to permit insertion of said container endwise into the refrigerator, the cover forming a closure for the orifice in the refrigerator casing, means for supporting the container within the refrigerator, and a wick below said container positioned to receive all drip from the exterior surface of said container and extending outwardly through the refrigerator casing. 15
12. In a refrigerator, an enclosed water-tight ice container in the form of a cylindrical vessel, a removable insulated cover for the open end thereof, the refrigerator casing having a circular orifice adapted to permit insertion of said container endwise into the refrigerator, the cover forming a closure for the orifice in the refrigerator casing, means for supporting the container within the refrigerator, and a wick below said container positioned to receive all drip from the exterior surface of said container and extending outwardly through the refrigerator casing. 20

HENRY LUCAS ROBERTS.
